CLAIM

I claim the ornamental design for a poker chip lighter, substantially as shown and described.

DESCRIPTION

FIG. 1 is a front perspective view of the poker chip lighter with its cap in a closed position.

FIG. 2 is a rear perspective view of FIG. 1.

FIG. 3 is a top plan view of FIG. 1.

FIG. 4 is a bottom plan view of FIG. 1.

FIG. 5 is a front perspective view of the poker chip lighter with its cap in an opened position; and,

FIG. 6 is a front perspective view of the poker chip lighter with its cap in an opened position and the ignition device in a position of use.

The broken lines are shown for illustrative purpose only and form no part of the claimed design.
